UNITED STATES PATENT OFFICE.

DAVID S. KENNEDY, OF BROOKLYN, NEW YORK, ASSIGNOR TO MERTHALER LINOTYPE COMPANY, A CORPORATION OF NEW YORK.

LINOTYPE-MACHINE.

No. 853,801.

Specification of Letters Patent.

Patented May 14, 1907.

Application filed March 5, 1907. Serial No. 360,723.

To all whom it may concern:

Be it known that I, DAVID S. KENNEDY, of the borough of Brooklyn, county of Kings, and State of New York, have invented a new and useful Improvement in Linotype-Machines, of which the following is a specification:

This invention has reference to the knives which are employed for trimming the side faces of linotypes or printing slugs after their delivery from the mold in which they are cast.

In the form shown it is intended more particularly for use in Mergenthaler linotype machines of the general organization represented in Letters Patent of the United States #436,532. In these machines, an ejector drives the slug or linotype out of the mold and between two parallel knives in the receiving galley, one of the knives being adjustable in relation to the other in order to dress or trim the slugs to the various standard thicknesses, as nonpareil, brevier, etc.

My improvement has in view a very speedy and accurate adjustment of the movable knife and the supporting of the same firmly against the strain and pressure to which it is subjected during the passage of the slugs.

To this end it consists essentially in combining with the movable knife a movable stepped bar for advancing and supporting the same; in the peculiar construction of the stepped bar with adjustable steps or shoulders; and in various other details of construction.

With the exception of the parts hereinbefore described, the machine may be in all respects of ordinary construction.

In the drawings,—Figure 1 is a perspective view from the front of my improved trimming-device applied to a Mergenthaler machine. Fig. 2 is a horizontal section on the line 2—2, Figs. 1 and 3. Fig. 3 is a vertical section on the line 3—3, Figs. 1 and 2. Fig. 4 is a side view of the adjusting lever and its locking devices. Fig. 5 is a section on the line 2—2, Fig. 3, through one of the adjustable steps or shoulders. Fig. 6 is a cross-section on the line 6—6, Figs. 2 and 3. Fig. 7 is a side elevation of the stepped bar or slide formed in a single piece.

Referring to the drawings, A represents the rigid main-frame of the machine, and A'

a metal block commonly known as the knife-block, bolted rigidly to the main-frame and serving to support the trimming-knives and their adjuncts. B and C represent the two upright parallel knives between which slugs are ejected and by which the opposite side faces of the slugs are trimmed.

The knife B is secured rigidly to the main-frame by bolts b, or other suitable means. The opposing knife C is secured by bolts c rigidly to a horizontal slide D supported and guided in the knife-block A', so that by moving the slide, the distance between the two knives may be varied. The slide D carries also two horizontal screws c', which are seated against the back of the knife C, as a means of adjusting the same on the slide so that it will be exactly parallel with the opposing knife, and also to prevent the knife from moving back out of position on the slide.

To permit the adjustment of the knife C on the slide D the holes in the knife through which the screws c pass are elongated slightly in a horizontal direction as indicated by the dotted lines in Fig. 2.

E represents a spring seated in the knife-block and acting between a shoulder thereon and a shoulder on the slide D, its tendency being to urge the slide outward and thereby increase the distance between the knives.

For the purpose of advancing the slide D against resistance of the spring and thus decreasing the distance between the knives, I provide a vertical slide F guided in the knife-block and provided with a series of steps or shoulders e projecting different distances toward the slide D, so that as the slide F is moved downward, these shoulders e will act one after another against a stud or projection d on the slide D and thus move the latter forward step by step.

The slide F may be made as in Fig. 7, in one piece with the steps or shoulders integral therewith. Inasmuch, however, as it is difficult to produce the solid stepped slide, which must be hardened and ground, with the necessary accuracy, I prefer to make the steps, as shown in Figs. 2, 3 and 5, in the form of threaded studs or screws. Thus formed, they may be turned forward through and beyond the slide the exact distances required and then locked permanently in place by means of tubular set-screws e', or equivalent screws, seated tightly against them.

The screws or studs may be cheaply constructed by automatic machinery, and being small, they may be tempered to an extreme degree of hardness. They may be adjusted 5 in approximately the required positions, and thereafter ground away at the operative ends to the exact height required, or they may be adjusted to their final position in the first instance.

10 In the event of either one of the steps wearing away, it need only be set forward to the required position. Ordinarily the steps are advanced, each beyond the next, one "point"; in other words, a distance equal to 15 the difference between one standard type body and the next,—for example, the difference between nonpareil and minion, or minion and brevier. The result is that as the slide F is moved step by step, the knife C 20 will be adjusted to trim slugs to the successive standard thicknesses. In some cases, however, it is desirable to produce slugs of intermediate or bastard thicknesses. In this connection the adjustable steps or shoulders are of especial advantage, since any one 25 of them may be adjusted, independently of the others, to set the knife in any required position.

The steps on the slide F may act directly 30 against the slide D, but I prefer to provide the latter, as shown, with the bearing stud or projection d' before referred to, and this for the reason that the stud separately constructed may be made very hard, the better to resist wear, and to be replaced, if worn, by another.

The slide F may be actuated by any suitable means, but I prefer to employ, as shown, a hand-lever H pivoted to the knife-block at 40 h, and having its rear end provided with a slot h' to receive a stud f on the slide F, as shown in Figs. 1 and 2, so that the movement of the lever may serve to raise and lower the slide F and thus effect instantaneous adjustment of the knife C.

The knife is moved positively toward its companion by the slide F and is supported thereby firmly in the required position. When the slide is raised, the knife will be permitted 50 to receive from its companion step by step under the influence of spring E.

The parts may be fitted with sufficient friction to remain in their adjusted positions, but I prefer to provide the lever H with a locking device. In the form shown, this consists of a 55 latch or lever h², pivoted to the side of lever H, and provided with two locking-pins h³, h⁴,

arranged to alternately enter holes h⁵ in a sector-plate or flange formed on the knife-block. The spring h⁶ acts on the latch h² and 60 tends to press the opposite end of the latter and the pins therein toward the locking holes, so that the pins will enter automatically and lock the lever and knives in their various positions. 65

It will be observed that the holes h⁵ are arranged in two rows and alternate as shown in Fig. 4. The holes in one row receive the pin h³, while those in the other row receive the pin h⁴. This arrangement is adopted for the 70 reason that it permits in a limited space the use of large pins and large holes.

Of course it will be understood that any other suitable means may be used for locking the lever in its various positions. 75

Having described my invention, I claim and desire to secure by Letters Patent:—

1. In a linotype machine, the combination of a movable knife, a spring tending to move the same in one direction, and a stepped slide 80 to move the same in the opposite direction, the steps of said slide being independently adjustable in height.

2. In a linotype machine, the combination of a knife-block, a slide mounted therein, the 85 knife secured rigidly to said slide, a spring tending to move the slide in one direction, a second slide having steps or shoulders to advance and support the first-named slide, a lever arranged to move the second slide, and 90 means for locking said lever in predetermined positions.

3. In a linotype machine, the combination of a knife-supporting slide, and an actuating member having independently adjustable 95 steps or shoulders; whereby the knives may be set to dress slugs to standard or bastard thicknesses, as demanded.

4. In combination, a support A', a slide D sustained thereby, a slide F provided with 100 adjustable steps e, a lever for moving said slide, and a spring acting on slide D in opposition to slide F.

5. In a linotype machine, a knife-adjusting member consisting of a body portion F, 105 screws or studs e, and locking screws e'.

In testimony whereof I hereunto set my hand this twenty third day of February, 1907, in the presence of two attesting witnesses.

DAVID S. KENNEDY.
